Patented Sept. 17, 1918.

UNITED STATES PATENT OFFICE.

MAGNUS HANSON, OF PELICAN RAPIDS, MINNESOTA.

WAGON-SPRING.

1,278,919.

Specification of Letters Patent. Patented Sept. 17, 1918.

Application filed July 26, 1917. Serial No. 182,976.

To all whom it may concern:

Be it known that I, MAGNUS HANSON, citizen of the United States of America, residing at Pelican Rapids, in the county of Otter Tail and State of Minnesota, have invented certain new and useful Improvements in Wagon-Springs, of which the following is a specification, reference being had therein to the accompanying drawing.

10 This invention relates to a wagon spring and has for its principal object the production of an efficient and novel structure which is so formed as to readily yield when either a light or a heavy load is placed thereon.

15 Another object of this invention is the production of a wagon spring wherein the flat leaf springs are connected by means of pivoted toggles and the levers are also connected by means of coiled springs so as to 20 form a yieldable structure.

With these and other objects in view this invention consists in general of certain novel combinations, constructions and arrangements of parts as will be hereinafter fully 25 described and claimed.

In the accompanying drawing:

Figure 1 is a rear elevation of the wagon spring showing the same in use.

Fig. 2 is a vertical section taken on the 30 line 2—2 of Fig. 1.

Fig. 3 is a horizontal section taken on the line 3—3 of Fig. 1.

Fig. 4 is a detail perspective view of one of the toggles.

35 Fig. 5 is a detail perspective view of one end of the flat spring.

Referring to the accompanying drawing by numerals it will be seen that the axle 1 is mounted upon the wheels 2, while this 40 axle 1 supports the block 3 carried by the tapering beam 4. The wagon bottom 5 is also provided with a depending block 6 and the spring, to be hereinafter described, is mounted in any suitable manner upon the 45 block 3 and supports the block 6, as shown in Fig. 1.

The lower leaf spring 7 is mounted upon the block 3, while the upper leaf spring 8 is secured to the block 6 and these leaf 50 springs 7 and 8 have bifurcated ends 9 adjacent which are formed the sleeves 10.

The levers 11 have comparatively broad bottom portions 12 in which are formed openings 13. These bottoms extend into the 55 bifurcated ends 9 of the springs 7 and 8 so as to cause the openings 13 to register with

the openings 10, thereby permitting pivot bolts 14 to pass through the sleeves 10 and the openings 13 for pivotally connecting the levers 11 upon 60 the ends of the leaf springs 7 and 8. The outer ends of the levers 11 are also provided with openings 15 through which the pivot bolts 16 extend for pivotally connecting the outer ends of the levers together as 65 shown in Fig. 1. The inner ends of the levers 11 are provided with openings 17 through which the hooked ends 18 of the coiled springs 19 extend. These coiled springs 70 extend in planes which intersect each other as shown in Fig. 1 so as to cause a coiled spring to connect one of the upper levers to one of the lower levers. Consequently, the tension of the coiled springs 75 will urge the inner ends of the levers toward each other, thereby causing the levers of each pair to have their inner ends spaced under normal conditions.

When the device herein disclosed is in use it will be seen that the tension of the coiled 80 springs 19 will space the inner ends of the levers apart, while the resiliency of the leaf springs 7 and 8 will cause the springs to extend evenly in horizontal planes when the wagon body 5 is empty. When, however, 85 the body is carrying a load, it is obvious that the leaf springs 7 and 8 will yield and will disclose the following action: Pressure of the block 6 upon the central portion of the leaf spring 8 will cause the leaf 90 spring to yield at its central portion, and draw downwardly upon its ends. The leaf spring 7, however, being firmly supported at its center by the block 3 will cause its ends to move downwardly. This pressure 95 exerted upon the ends of these leaf springs will cause the pressure exerted upon the levers 11 to be an off-center pressure with respect to the pivot bolts 16. As a consequence, the inner ends of the levers will be 100 swung toward each other, thereby drawing upon the coiled springs 19. It is, of course, obvious that the degree of yielding of the leaf springs 7 and 8 and of the coiled springs 19 will vary according to the weight 105 of the load carried within the wagon body 5. It will be seen, however, that because of the resilient nature of the leaf springs and the tension of the coiled springs, a structure is provided which will readily 110 yield under all conditions and thus yieldably support the wagon body.

What is claimed is:

1. In a device of the class described, the combination of a pair of leaf springs, said leaf springs having bifurcated ends, levers pivotally connected to each other, said levers also being pivotally connected to the bifurcated ends of said leaf springs, and springs for normally urging the inner ends of said levers apart, said leaf springs being adapted to be mounted upon a wagon axle and support a wagon body whereby when pressure is exerted upon said leaf springs said levers will be swung toward closed positions so as to yieldably support the wagon body. 2. In a device of the class described, the combination of a pair of leaf springs, said leaf springs having bifurcated ends, sleeves formed upon the ends of said leaf springs, levers comprising elongated girdles which are broadened at their central portions, said levers projecting within the bifurcated ends of said leaf springs, pivot bolts passing through said sleeves and said levers for pivotally maintaining said levers upon said sleeves, pivot bolts pivotally connecting the outer ends of the levers whereby said levers will be pivotally mounted in pairs upon each end of the leaf spring arrangement, coiled springs connected to the inner ends of said levers, said coiled springs extending in planes intersecting each other in such manner that each coiled spring will connect one of the upper levers or one of the lower levers, thereby causing the levers to be normally held in open positions at their inner ends, said leaf springs being adapted to be mounted upon the axle of a wagon and support the body thereof whereby when pressure is exerted upon the coil springs said levers will be swung to closed positions against the tension of said coiled springs for yieldably supporting the wagon body.

In testimony whereof I hereunto affix my signature.

MAGNUS HANSON.
